COVER FOR BINDERS

Filed Sept. 3, 1929

UNITED STATES PATENT OFFICE

OZANAM SEGUIN, OF ST. DOMINIQUE-DES-CEDRES, QUEBEC, CANADA

COVER FOR BINDERS

Application filed September 3, 1929, Serial No. 390,070, and in Canada March 21, 1929.

The present invention pertains to a novel cover for a binder machine of the type embodying a reel, a platform and elevators on the platform. The primary object of the invention is to provide a cover of this character adapted to be drawn over the elevators in order to protect the same and the mechanism comprised therein.

The device of the invention includes essentially a sheet of covering material, such as canvas, having one end secured to a spring tension roller. This roller is preferably supported at one end of the platform by being journaled between the side frame members of the upper elevator. In idle condition, the covering member is wound on the roller, but in service is withdrawn therefrom and has its free end suitably attached to the opposite end of the platform.

The invention is fully disclosed by way of example in the following description and in the accompanying drawings in which

Figure 1 is a perspective view of a binder, showing the device of the invention applied thereto;

Figure 2 is a perspective view of the cover;

Figure 3 is a sectional view of the spring tension roller and the side frame members carrying the same;

Figure 4 is a section on the line 4—4 of Figure 1, and Figure 5, is a detail section of the cover.

Reference to these views will now be made by use of like characters which are employed to designate corresponding parts throughout.

In Figure 1 is illustrated an agricultural binder, the essential parts of which are the reel 1, the platform 2, the lower elevator 3, and the upper elevator 4. It will be seen that the latter is disposed between a pair of side frame members 5 and 6 which are fixed with reference to the machine. This construction is now in use and is known on the market as the McCormick binder.

To the inner faces of the members 5 and 6, at the upper ends thereof, are attached brackets 7 and 8 respectively. A rod 9 is supported in the brackets, having one end 10 journaled in the member 8 and a square end 11 mounted in the bracket 7. On the rod 9 is rotatably

supported a roller 12 having a recess 13 at one end. The recess contains a tension spring 14 coiled around the rod, with one end 15 fixed to the roller and the other end 16 fixed to the end 11 of the rod 9.

To the roller 12 is attached a sheet of suitable covering and protecting material 17 adapted to be wound upon the roller by the action of the spring 14 therein. This sheet is of a two-ply character, as indicated by the numerals 18 and 19 in Figure 5, and is reinforced at intervals by transverse strips or bars 20, disposed between the plies.

In use, the covering sheet is drawn out over the platform 2 by means of a string 21 at the free end of the sheet. This end also carries a series of hooks 22 adapted to engage the corresponding end of the platform, thereby holding the sheet in its drawn out condition against the tension of the spring 14. Obviously, when the hooks are released from the platform, the cover will be drawn up on the roller 12, by the action of the spring 14.

The sheet 17 is passed beneath a transverse frame member 23 of the binder machine, serving ordinarily to support the seat 24. The cover is held spaced from the member 23 and is permitted to pass freely beneath the same by means of wire shoes 25 carried by the transverse member and presenting curved portions 26 to the upper surface of the sheet.

Inasmuch as the upper elevator confined between the side members 5 and 6 is narrower than the lower elevator 3, and the sheet 17 on the roller 12 is in turn narrower than the upper elevator, I provide auxiliary means for covering the margins of the lower elevator. This means consists of angle bars 27 secured to the outer faces of the side frame members 5 and 6 and extending along the longitudinal edges of the platform, thereby constituting side shields for the margins of the lower and wider elevator 3 as shown more clearly in Figures 1 and 3.

Although a specific embodiment of the invention has been illustrated and described, it will be understood that various alterations in the details of construction may be made without departing from the spirit of the invention as indicated by the appended claims.

Having thus fully disclosed my invention, what I claim and desire to secure by Letters Patent is:—

1. In combination with a binder including a reel, a platform adjacent said reel, and elevators on said platform; a spring tension roller at one end of said platform, a cover for said platform having one end attached to said roller, means at the other end of said cover for attachment to the remaining end of said platform, and transverse reinforcing strips secured to said cover.
2. In combination with a binder including a reel, a platform adjacent said reel, upper and lower elevators on said platform, the upper elevator being narrower than the lower elevator and having side frame members; a tension roller supported by said frame members, a cover attached to said roller and adapted to be drawn over said elevators, and shields secured to said frame members and extending over the margins of said lower elevator.
3. In combination with a binder including a reel, a platform adjacent said reel, and elevators on said platform; a cover attached to one end of said platform and having means for attachment to the other end of the platform, a transverse frame member over said elevators, and spacer shoes carried by said member and adapted to engage said cover.
4. In combination with a binder including a reel, a platform adjacent said reel, upper and lower elevators on said platform, the upper elevator being narrower than the lower elevator and having side frame members; a tension roller supported by said frame members, a cover attached to said roller and adapted to be drawn over said elevators, shields secured to said frame members and extending over the margins of said lower elevator, and transverse reinforcing strips secured to said cover.

In witness whereof I have hereunto set my hand.

OZANAM SEGUIN.
